UNITED STATES PATENT OFFICE.

CRANSTON H. CARPENTER, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC FURNACE.

1,409,669.

Specification of Letters Patent. Patented Mar. 14, 1922.

Application filed August 6, 1920. Serial No. 401,679.

To all whom it may concern:

Be it known that I, CRANSTON H. CARPENTER, a citizen of the United States, and a resident of Irwin, in the county of Westmoreland and State of Pennsylvania, have invented a new and useful Improvement in Electric Furnaces, of which the following is a specification.

My invention relates to electric furnaces and, particularly, to electric furnaces where in heat is produced by the flow of current through the receptacles containing the material to be treated.

One object of my invention is to provide an electric furnace of the above-indicated type that shall be efficient and economical in operation and that shall be provided with easily removable conducting lugs for connecting the receptacle to be heated to the source of energy.

In an electric furnace constructed in accordance with my invention, a crucible, composed of any suitable conducting material, such as a mixture of graphite and clay, is surrounded by walls composed of refractory material. Within such walls are located two compartments containing finely divided conducting material which is connected to the contact terminals of the electric circuit through which energy is supplied to the furnace. Two lugs are detachably connected to the crucible and extend into the compartments containing the powdered conducting material. The outside portions of the walls surrounding the crucible are preferably composed of some suitable heat-insulating material.

In the accompanying drawing, Figure 1 is a plan view and Fig. 2 is a sectional elevational view of an electric furnace constructed in accordance with my invention.

Referring to the drawing, a crucible 1, which is composed of any suitable conducting material, such as a mixture of graphite and clay, is provided with projections 2 and 3. The crucible is surrounded by walls 4 having inside surfaces composed of any suitable refractory material. An opening 5 is formed in the front wall for permitting the pouring of the material contained within the crucible. The outside portions of the walls surrounding the crucible 1 are preferably composed of any suitable heat-insulating material.

Two compartments 6 and 7 are formed in the wall surrounding the crucible and contain powdered conducting material, as, for example, finely divided graphite. The contact terminals 8 and 9 of the electric circuit connected to the furnace are disposed in the bottom of the compartments 6 and 7. Pressed coke electrodes 10 and 11 are provided for connecting such contact terminals to the finely divided conducting material contained within the compartments 6 and 7. Two lugs 12 and 13, which project into the compartments 6 and 7, are detachably connected, in any suitable manner, to the projections 2 and 3 on the sides of the crucible 1. Preferably, threaded extensions 14 and 15 are provided for connecting the lugs 12 and 13 to the projections 2 and 3.

Trunnions 16 and 17 are mounted on the outside portions of the furnace for permitting the tilting of such furnace to pour the material contained within the crucible 1. In operating the furnace, electric current is transmitted from the contact terminal 8, through the block 11, the powdered conducting material contained within the compartment 7, lug 13, projection 3, crucible 1, projection 2, lug 12, the powdered conducting material contained within the compartment 6, and block 10, to the contact terminal 9. The passage of current through the crucible 1 evenly heats such crucible for melting the material contained within it. The powdered conducting material contained within the compartments 6 and 7 is very easily renewed and, moreover, the lugs 12 and 13, which connect the crucible to such powdered conducting material, are easily renewed without renewal of a complete crucible.

Modifications in the furnace and in the arrangement and location of parts may be made within the spirit and scope of my invention, and such modifications are intended to be covered by the appended claims.

I claim as my invention:

1. In an electric furnace, the combination with a crucible having two projections extending therefrom, of lugs detachably connected to said projections and extending into compartments containing granular material.
2. In an electric furnace, the combination comprising a crucible having detachable lugs connected thereto, granular conducting

100

105

material surrounding the ends of said lugs, and contact terminals connected to said granular material.

3. In an electric furnace, the combination comprising a crucible having lugs threadably connected to it, compartments containing granular graphite surrounding the ends of said lugs, and contact terminals in circuit with said granular graphite.

10 4. In an electric furnace, the combination with a crucible composed of conducting material, walls of refractory material surrounding said crucible and two projecting portions extending from said crucible, of two lugs detachably connected to the projections on said crucible and projecting through said refractory walls into compartments containing granular graphite, and terminal conductors connected to the graphite in said compartments.

15 5. In an electric furnace, the combination

with a crucible composed of conducting material and having projections extending therefrom, of lugs detachably connected to said projections and extending into compartments containing granular conducting material.

20 6. In an electric furnace, the combination with a crucible composed of conducting material and having two projections extending therefrom, and a refractory wall surrounding said crucible, of two compartments in said wall containing finely divided conducting material, lugs detachably connected to said projections and extending into said compartments, and terminal conductors connected to the conducting material contained in said compartments.

25 In testimony whereof, I have hereunto subscribed my name this 30th day of July, 1920.

CRANSTON H. CARPENTER.
